(57) **CLAIM**

The ornamental design for a toy tree for a toy building set, as shown and described.

DESCRIPTION

FIG. 1 is a front, top perspective view of a first top piece of a toy tree for a toy building set, shown separated for ease of illustration, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective view of a second top piece of the toy tree for a toy building set, shown separated for ease of illustration;

FIG. 10 is a rear, bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, top perspective view of a third top piece of the toy tree for a toy building set, shown separated for ease of illustration;

FIG. 18 is a rear, bottom perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof;

FIG. 24 is a bottom plan view thereof;

FIG. 25 is a front, top perspective view of a fourth top piece of the toy tree for a toy building set, shown separated for ease of illustration;

FIG. 26 is a rear, bottom perspective view thereof;

FIG. 27 is a front elevation view thereof;

FIG. 28 is a rear elevation view thereof;

FIG. 29 is a left side elevation view thereof;

FIG. 30 is a right side elevation view thereof;

FIG. 31 is a top plan view thereof;

FIG. 32 is a bottom plan view thereof;

FIG. 33 is a front, top perspective view of a bottom piece of the toy tree for a toy building set, shown separated for ease of illustration;

(Continued)

FIG. 34 is a rear, bottom perspective view thereof;

FIG. 35 is a front elevation view thereof;

FIG. 36 is a rear elevation view thereof;

FIG. 37 is a left side elevation view thereof;

FIG. 38 is a right side elevation view thereof;

FIG. 39 is a top plan view thereof;

FIG. 40 is a bottom plan view thereof;

FIG. 41 is a front, top perspective view of the toy tree for a toy building set, shown in a fully assembled configuration;

FIG. 42 is a rear, bottom perspective view thereof;

FIG. 43 is a front elevation view thereof;

FIG. 44 is a rear elevation view thereof;

FIG. 45 is a left side elevation view thereof;

FIG. 46 is a right side elevation view thereof;

FIG. 47 is a top plan view thereof;

FIG. 48 is a bottom plan view thereof;

FIG. 49 is a front, top perspective view of the toy tree for a toy building set, shown in a fully assembled configuration and in an alternate position; and,

FIG. 50 is a rear, top perspective view thereof.
